UNITED STATES PATENT OFFICE.

ERNEST M. WHITNEY, OF PROVIDENCE, RHODE ISLAND.

FASTENER.

Application filed March 30, 1925. Serial No. 19,332.

This invention relates to an improved construction of separable fastener, and has for its object to provide a fastener of this character, which comprises two rows of interlocking members for releasably locking together adjacent edges of an article, such as shoes, boots, overshoes, or other article, and the particular feature of this invention is the provision of an operating device 5 ably mounted on these rows of interlocking members and having locking means whereby said device is retained in any desired adjusted position along the rows of the interlocking members.

15 A further object of this invention is to mount a pair of oppositely-disposed operating plates to slide upon the interlocking members and to provide a pull member with means for clamping these plates upon 20 these rows of interlocking members to lock the device in adjusted position thereon.

With these and other objects in view, the invention consists of certain novel features of construction, as will be more fully described, and particularly pointed out in the appended claims.

In the accompanying drawings:

Figure 1 is a front elevation showing my improved separable fastener with its upper 30 ends separated.

Figure 2 is a sectional view on line 2—2 of Figure 1, showing my improved means for locking the operating device in adjusted position.

35 Figure 3 is a perspective view illustrating the bottom operating plate with the upper plate removed.

Figure 4 is another view of the bottom operating plate.

40 Figure 5 is a perspective view of the under side of the cam pull member.

Figure 6 is a sectional elevation illustrating the locking cam as acting upon the plates to bind them against the opposite 45 edges of the rows of interlocking members.

Figure 7 is a perspective view illustrating the cam pull in position to spring the plates together and bind them together in the interlocking members to retain them in adjusted 50 position.

Figure 8 is a modified construction showing an edge view of the fastener and illustrating the clamping member as secured in position by a padlock.

55 It is found in the practical construction and operation of separable fasteners of this

character, particularly where they are applied to shoes, overshoes, and other like devices in which an opening strain is brought to bear upon the parts to separate their adjacent edges by sliding the operating device towards opening position, to be very annoying to the wearer, and to obviate this difficulty, I have provided a locking or clamping attachment to act upon the operating members of the operating device to readily lock the same in any desired adjusted position along the length of the fastener; and the following is a detailed description of the present embodiment of my invention 60 showing one means by which this advantageous result may be accomplished.

With reference to the drawings, 10 designates the strip of material, to the opposite edges of which the usual interlocking metallic members 11 are applied, and the operating device 12 which is constructed of a pair of spaced plates 13 joined by a resilient loop 14 acting to connect the opposite edges of the interlocking members to normally hold these plates in spaced relation and these plates are provided with the usual edge flanges 15 to engage and force these locking members into and out of interlocking position; also these plates are provided 70 with diverging portions 16 at their upper ends which serve to guide and separate the members when the operating device is moved in a direction to either engage or disengage these sets of members one with the other.

It is found in practice that when the usual separable fastener of this character is applied to such articles as overshoes and the like, that when a separating strain is applied to the upper edge thereof, that this operating device 12 has a tendency to slip downward along the fastening members and permit the top of the shoe to open or spread to the annoyance of the wearer, and to obviate this difficulty, I have provided means for drawing together the opposite plates 13 of this member and cause them to grip and bind the interlocking members and so effectually prevent this device from inadvertently sliding from set position even when acted upon 80 by extraordinary strains.

To accomplish this locking or binding action in a simple and effective way, I have formed a staple-shaped connector 17, preferably with two legs 18 that extend down 90 through the top plate and are headed over through openings in the bottom plate, the

loop portion of this staple being arranged to extend above the top plate.

In order to draw these plates toward each other, I have formed a cam-shaped member 5 19 on the end of the pull lever 20. This cam member has a portion extending laterally through the eye 17 of the staple with its cam edges 21 resting upon the upper face of cam edges 21 resting upon the upper face of the top plate, the cam being so shaped that 10 when the handle of the pull is moved towards the down position to lie against the top plate the cam serves to act upon this plate and also through the staple upon the bottom plate to draw or force these plates 15 toward each other and so bind them against the opposite edges of the interlocking members 11; also the edge portion of this cam is set on such an angle as to extend just beyond the vertical center line through the loop so 20 as to retain the handle of the pull in its down or locked position.

By this construction, it will be seen that the handle member serves as a convenient pull for the operating member by which it 25 may be caused to slide either up or down into the desired position and then by swinging the lever down upon the top plate both plates are drawn toward each other to bind the whole together.

30 I have shown the cam edges of the pull member as engaging the back of the top plate to draw the two plates toward each other to bind them on opposite sides of the interlocking members 11, but any suitable 35 means may be employed to effect this binding action without departing from the spirit and scope of this invention.

It is found in practice where my improved 40 device is applied as a fastener for such articles as traveling bags or other similar receptacles, of advantage to lock the same so as to prevent it from being opened by an unauthorized person, and to accomplish this in a simple and effective way, I have formed 45 an eye member 22 on one of the loops 23 for the reception of a padlock 24, or other locking device, whereby the cam binding member 19 may be secured in locked position when desired.

50 The foregoing description is directed solely towards the construction illustrated, but I desire it to be understood that I reserve the privilege of resorting to all the mechanical changes to which the device is susceptible, 55 the invention being defined and limited only by the terms of the appended claims.

I claim:

1. A fastener comprising two rows of co-operating interlocking members for releasably connecting together adjacent edges of an article, a fastener operating device comprising cooperating inner and outer plates 60 slidably mounted on said rows, and binding means acting directly upon said plates to grip the intermediate fastener parts between 65

them and so retain said device in any adjusted position along the length of said members.

2. A separable fastener comprising two rows of cooperating interlocking members 70 for releasably connecting together adjacent edges of an article, a pair of oppositely-disposed operating plates slidably mounted thereon, and means for binding said plates on said members to retain the plates in adjusted position. 75

3. A separable fastener comprising two rows of cooperating interlocking members for releasably connecting together adjacent edges of an article, an operating device comprising a pair of oppositely disposed spaced 80 plates having diverging channels, and a cam movable to bind said plates against said members to retain the device in adjusted position. 85

4. A separable fastener comprising two rows of cooperating interlocking members for releasably connecting together adjacent edges of an article, an operating device comprising a pair of oppositely disposed spaced 90 plates having diverging channels, and a pull handle for manipulating said device and having a cam portion acting upon said plates causing them to grip said members when in any desired adjusted position by the 95 swinging of the handle downward.

5. A separable fastener comprising two rows of cooperating interlocking members for releasably connecting together adjacent edges of an article, an operating device comprising a pair of oppositely disposed spaced 100 plates connected by a resilient loop, a connector between said plates, and means arranged to operate through said connector for binding said plates against said members to lock the device in adjusted position. 105

6. A separable fastener comprising two rows of cooperating interlocking members for releasably connecting together adjacent edges of an article, an operating device comprising a pair of oppositely disposed spaced top and bottom plates connected by a resilient loop, a connector between said plates having a portion extending through the top plate, and a cam having an operating handle arranged to engage the upper portion of said connector for causing said plates to grip said members to lock the device in adjusted position. 110

7. A fastener comprising two rows of co-operating interlocking members for releasably connecting together adjacent edges of an article, a fastener operating device comprising cooperating inner and outer plates 115 slidably mounted on said rows, pressure exerting means acting directly upon said plates to grip and retain said device in any desired adjusted position along the length of said interlocking members, and a lock for secur- 120

ing said retaining means in binding position.

8. A separable fastener comprising two rows of cooperating interlocking members for releasably connecting together adjacent edges of an article, an operating device comprising a pair of oppositely disposed spaced

plates having diverging channels, a cam movable to bind said plates against said members to retain the device in adjusted position, and a lock for securing said cam in binding position.

In testimony whereof I affix my signature.
ERNEST M. WHITNEY.
